CONTROL OF RADIOCIRCUITS

Application filed February 24, 1925. Serial No. 11,222.

This invention relates to the control of radio circuits and more particularly to means for facilitating the tuning of related circuits.

The various systems of related circuits which are employed in radio communication for receiving or transmitting signals, are controlled similarly to produce an optimum condition for any particular wave length or frequency by the adjustment of one or more tuning reactors and by such adjustment a condition approaching resonance is produced in the individual circuit or circuits. Most systems in common use involve two or more coupled circuits, one of which includes the antenna or equivalent device. This latter circuit has markedly different electrical characteristics from those composed principally of lumped capacities and inductances, chiefly because of the distributed capacity of the antenna itself.

20 Whenever it is desired to bring each of the related circuits to its optimum condition, each of the tuning reactors with which the circuits are commonly provided, such as a variable inductance or a variable capacity, must be 25 separately adjusted. Proposals to interconnect mechanically several of these tuning devices have, however, usually not included a tuning reactor for the antenna circuit because, for reasons stated above, it is not easy to find a 30 simple relation between the necessary adjustments for the antenna circuit and the other circuits with which it is coupled.

In a radio receiving system which includes two or more circuits other than the antenna circuit having therein individual tuning reactors or controlling devices, it is possible, provided the design is such that the settings of similarly calibrated dials attached to said devices are identical for every frequency 40 within the range of the receiver, mechanically to interconnect the movable parts of said devices so that they will move in a predetermined ratio, as by gears, belted pulleys, or by mounting them on a single shaft, and thus 45 allow control of these devices through a single dial. In an antenna circuit, on the other hand, in which the reactance and chiefly the inductance and capacity are distributed, or in a circuit in close inductive relation thereto, 50 the character of the variation of reactance

with changes of frequency is dissimilar to the character of the same variation in a circuit having only lumped inductances and capacities and it has heretofore been found impossible to obtain like or readily comparable dial settings with those of other related circuits not affected by the changing characteristics of the antenna circuit.

55 One object of the present invention is to provide an arrangement which will facilitate the simultaneous tuning of related circuits of different electrical characteristics.

In accordance with a feature of the invention, a compensating reactor is placed in one of the circuits which is constructed and arranged to supplant or to assist the usual tuning device in bringing said circuit approximately to resonance when other circuits with which it is related have been tuned by their 60 tuning reactors.

65 Another object of the invention is to devise improved means for effecting, by the mechanical movement of a single part, the simultaneous tuning of coupled circuits of which one includes the antenna circuit. Owing to 70 causes including the distributed reactance, i. e., the distributed inductance and capacity, of the antenna circuit, the movements of the tuning reactor such as a variometer or condenser in this circuit required to bring this 75 circuit into resonance for use with signals of a particular frequency are dissimilar to and not readily comparable with the changes required to cause the tuning reactor in the circuit 80 coupled to the antenna circuit to bring its 85 circuit simultaneously to resonance. Clearly, this problem is accentuated when it is attempted to design a radio receiving set suitable for use with various antennae. Another 85 feature of the invention relates to an arrangement for simultaneously tuning coupled circuits, one of which includes the antenna, by the movement of a single operator-controlled device. In the illustrated arrangement, both 90 the circuit which includes the antenna and the circuit or circuits coupled thereto are provided with tuning reactors, here condensers, and the operating controls of these reactors are mechanically connected for movement in 95 a predetermined ratio under the impulse of a 100

single operator-controlled device. In the antenna circuit, a compensating reactor is provided which is arranged to for control by the single operator-controlled device and is also constructed and arranged so that the rate of change of reactance produced by movement of its relatively movable parts may be varied and determined in accordance with the characteristics of the particular antenna circuit.

In the illustrated construction, the compensating reactor has relatively movable elements and means for varying the rate of change in the combined reactance of said elements produced by similar relative movements thereof and the parts are arranged as a variometer having stator and rotor windings with means for adjusting the linkage of the fluxes of the two windings by adjusting the position of the stator winding with respect to the path of rotation of the rotor.

These and other features of the invention will be best understood from a consideration of the following specification taken in connection with the accompanying drawings, in which:

Fig. 1 is a diagram illustrating one specific application of the invention to a reflex receiving system.

Fig. 2 is a diagram illustrating another application of the invention, to a simple crystal receiving system.

Fig. 3 shows one form of a compensating reactor constructed for use with my invention and mechanically coupled to a plurality of tuning condensers.

Although my invention is applicable to radio circuits for various systems and for either receiving or transmitting systems, I shall, in order to facilitate explanation of the invention, discuss it only in connection with receiving systems and no limitation to any particular system or class of systems should be implied therefrom.

In the particular system illustrated in Fig. 1, which I have found to be one effective application of the invention, the antenna circuit includes an antenna 10, a compensating reactor in the form of a special adjustable variometer 12, an adjustable loading coil 14, the coil 16 of a coupler, and a variable condenser 18, the rotor plates of which are grounded at 20.

Energy received in the antenna circuit is fed to the grid circuit of a vacuum tube 25, of the well-known three element type, through the other coil 22 of the coupler, and the circuit is tuned by means of a variable condenser 24 bridged across said coil and connected at one terminal to the grid 26 of the tube and at the other terminal to the filament 28 of said tube. Direct current may be supplied to the filament 28 from a suitable battery 30 under the control of a rheostat 32.

The circuit from the plate 34 of the vac-

uum tube 25 is arranged to be tuned by a variable condenser 36 in shunt with an inductance 38, both of which are bridged across a crystal 40 and the primary winding 42 of an audio frequency transformer. The plate circuit is completed through telephones 44 and a battery 46 to the filament 28.

The current flowing in the primary winding 42 induces a current in a secondary winding 48 of the audio frequency transformer which is fed back into the grid circuit by bridging the terminals of the secondary winding 48 across a fixed condenser 50 in said grid circuit. Preferably a by-pass fixed condenser 52 is shunted across the telephones 44 and the battery 46 while another by-pass fixed condenser 54 is shunted across the primary winding 42 of the audio frequency transformer.

The tuning reactors 18, 24, and 36 and the compensating reactor 12 are arranged for control by a single operator-controlled device 56. Preferably the movable parts of said reactors are mechanically interconnected so that they will move in a predetermined ratio as, for example, by mounting the rotors of the condensers 18, 24, and 36 and the rotor of the compensating variometer 12 upon a single shaft, with the various rotors insulated from one another.

The compensating reactor may be constructed as indicated in Fig. 3 as a novel form of adjustable variometer having relatively movable electrical parts 60 and 68 constructed and arranged so that the rate of variation of reactance, here largely inductance, may be controlled. To this end stator windings 60 and 62, which are shown as hollow hemispheres, are mounted upon adjustable supporting brackets 64 and 66 by means of which the position of one or both of said stator windings may be adjusted to control the proportion of the flux produced thereby which is cut by a rotor winding 68. In other words, adjustment of one of the electrical parts of the compensating reactor, here adjustment of the position of the stator windings 60 and 62, enables the operator to vary the rate of change of reactance produced by movement of the rotor winding 68 and hence its characteristic curve. In one adjusted position of the stator windings, the incremental change of reactance may be one ohm for each degree of rotation, for example, producing a rate of change of one ohm per degree. In another position of adjustment of the stator windings, the rate may be three ohms per degree, but it will be understood that these figures are merely illustrative and have no relation to any particular circuit. This rotor winding is approximately spherical in form and is connected in series with and intermediate between the stator windings 60 and 62. The rotor winding 68 may be supported for rotation upon a shaft 130

5 journalized in bearings 70 and provided with an operator-controlled device 72. The compensating reactor or variometer is shown here as connected directly to an antenna 74 but this is merely indicative of its position in the particular circuit shown in Fig. 1 and should not be construed as limiting its use to such a position or connection. The particular form of the winding illustrated may 10 be replaced by other well-known types such as the "figure 8" type without affecting the operation of the device.

15 It should be noted that the compensating reactor need not provide the total inductance used in tuning the antenna circuit but only a sufficient amount to compensate for the effect of the antenna upon the circuit. Sufficient additional inductance to adapt the receiver to the required wave length range is then 20 provided by the series loading coil 14, tapped to secure fine variation.

25 I find it convenient so to arrange the stator windings 60 and 62 with respect to the rotor winding 68 and the rotors of the variable condensers 18, 24, and 36 that, when all 30 of said condensers are set in a minimum position, the inductance of the compensating variometer will also be a minimum for the particular angular positions of the stator windings and that, when the condensers are set in a maximum position, the inductance of the variometer will also be a maximum for the particular positions of the stator windings.

35 One satisfactory and practical method of determining the proper position of the stator windings of the compensating reactor or variometer so that said variometer will be effective in connection with a particular 40 antenna is as follows:—Having placed the stator windings at some arbitrary point such as that indicated in the drawings, a signal of low wave length should be tuned in by manipulation of the operator-controlled device indicated at 56 or at 72 and variation 45 of the loading coil 14. The position of the tap switch for the inductance coil 14 should be noted and then a signal of high wave length tuned in. If, in tuning in the signal of higher 50 wave length, it is found necessary to increase the inductance of the coil 14, the stator windings of the variometer should be moved to a position nearer the rotor, but, if it is found necessary to decrease the inductance of the 55 coil 14 at the higher wave length, then the stator windings of the compensating variometer should be adjusted to a position farther away from the rotor. This operation should be repeated for a variety of wave 60 lengths until a position of the stator windings is found at which the setting of the tapped coil 14 will be the same for high and low and intermediate wave lengths. At this position, the compensating reactor will become effective to perform the functions already de-

scribed so that the system may be effectively tuned simply by the operation of a single device 56.

The invention may be applied to many circuits using many combinations of apparatus without affecting the principles involved. One other application, to a two circuit crystal receiver employing a loosely coupled antenna circuit and a tuned secondary circuit, is shown in Fig. 2. Here an antenna 76 is connected through the compensating reactor 78 and a tapped coil 80 of a vario-coupler to an adjustable condenser 82 and thence to ground 84. Another coil 86 of the vario-coupler is included in a secondary circuit, tuned by a variable condenser 88 and including a crystal 90 and telephones 92, the latter being bridged by a by-pass fixed condenser 94. A single operator-controlled device 96 is provided for the compensating reactor 78 and the condensers 82 and 88.

Having thus described my invention, what I claim as new and seek to cover by Letters Patent of the United States is:

1. In a radio system having a plurality of 50 circuits to be tuned, tuning reactors for said circuits, each of said reactors having a movable part the mechanical movement of which produces changes in reactance, one of said circuits having a distributed reactance, a 55 variable compensating reactor in the last-mentioned circuit having a movable part by the movements of which changes in its reactance are produced, means for varying the rate of variation in reactance of the compensating reactor produced by changes in the 60 mechanical position of its movable part, and means for mechanically interconnecting the movable parts of said tuning reactors and said compensating reactor constructed and 65 arranged to move them in a predetermined ratio.

2. In combination, means for simultaneously tuning related circuits of different electrical characteristics comprising mechanically coupled tuning reactors, said means including a compensating reactor in one of said circuits having relatively movable electrical parts one of which is adjustable to vary the characteristic curve of the reactor, said 70 compensating reactor being constructed and arranged when said adjustable part has been preliminarily adjusted, to bring said circuit to resonance simultaneously with the tuning 75 of the other circuit by manipulation of its 115 tuning reactor.

3. In combination, coupled circuits, one of said circuits having a markedly distributed reactance, the other of said circuits having a substantially lumped reactance, variable tuning reactors in said circuits, a single operating means for said reactors arranged to vary them in a predetermined ratio, a compensating reactor in said first-mentioned circuit having relatively movable coils, 120

and means for varying the incremental changes in reactance of said compensating reactor produced by successive equal movements of one of the coils constructed and arranged to make said reactors simultaneously effective to tune their circuits when moved by the single operating means.

4. In combination, coupled circuits, one of said circuits having a markedly distributed reactance, the other of said circuits having a substantially lumped reactance, variable tuning reactors in said circuits, a compensating reactor in one of said circuits, a single operating means for said tuning and compensating reactors arranged to move them together equal amounts, and means to vary the resultant reactance of the compensating reactor accompanying said movements to the end that the reactor in the same circuit will be enabled to bring its circuit to approximate resonance when resonance of the other circuit has been attained by adjustment of its tuning reactor.

5. In combination, inductively coupled circuits, one of said circuits having a markedly distributed capacity, the other of said circuits having a lumped capacity, variable tuning reactors in said circuits, a single operating means for said reactors arranged to vary them in a predetermined ratio, a compensating inductor in said first-mentioned circuit also controlled by said operating means, and means for varying the effect on the inductance of said compensating inductor produced by equal movements of said operating means whereby said reactors will be simultaneously effective to tune their circuits when moved by the single operating means.

6. In combination, means for tuning simultaneously related circuits of different electrical characteristics comprising tuning reactors in said circuits including a compensating reactor in one of said circuits having relatively movable windings, means for varying the amount of change in the combined reactance of said windings produced by similar relative movements thereof, and a single operator-controlled device for bringing the circuits simultaneously into an optimum condition for use with signals of a particular frequency, said device being arranged to control said tuning reactors and said compensating reactor.

7. A single dial control for a radio receiving set arranged simultaneously to control and bring to an optimum condition for the reception of signals of any particular wave length the antenna circuit and another circuit by moving together both the tuning reactor in the latter circuit and also a compensating device in the antenna circuit, said compensating device having relatively movable parts and being provided with means to vary the interaction of the parts in similar positions of one part, thereby to offset the

detuning effect of the distributed capacity in the antenna.

8. A radio receiving system including an antenna circuit having a tuning condenser and a compensating variometer, means for varying the relative path of movement of the windings of said variometer to control the rate of change of inductance produced by relative movement of the windings, another circuit inductively coupled to said antenna circuit having a tuning condenser, and a single operator-controlled dial connected mechanically to and arranged to control simultaneously said condensers and said variometer, thereby to tune both circuits for signals of any particular wave length.

In testimony whereof I have signed my name to this specification.
